UNITED STATES PATENT OFFICE.

JOHN FINK, OF NEW YORK, N. Y.

SEWING-MACHINE.

1,107,599.

Specification of Letters Patent. Patented Aug. 18, 1914.

Application filed February 12, 1914. Serial No. 818,183.

To all whom it may concern:

Be it known that I, JOHN FINK, a citizen of the United States, and resident of the city, county, and State of New York, have 5 invented a certain new and useful Improvement in Sewing-Machines, of which the following is a specification.

My invention relates to that class of sewing or embroidery machines in which cording or analogous material is secured to fabric by means of a thread carried around or 10 through said material and around the thread of stitching formed on the fabric.

More particularly my invention relates to 15 a device by means of which machines of this class may be utilized to attach spangles, as they are commonly sold in strip or tape form, to the fabric by concealed stitches.

A further object of my invention is to 20 provide a device of the character specified by means of which two strips or tapes of spangles may be simultaneously stitched to the fabric so as to constitute an ornamental, pleasing and unitary stripe of ornamentation thereon.

My invention will be better understood by reference to the drawings in which—

Figure 1 represents, in front elevation, a view of a part of the head of a standard embroidery machine of the type specified, said head being provided with the device of my invention as made to attach a single strip of spangles; Fig. 2 is a view taken from the right of Fig. 1; Fig. 3 an enlarged detail 35 view, taken from the same point of view as Fig. 2 but showing only the device proper as it appears while the strip of spangles is actually being sewed upon the fabric; Fig. 4 shows a plan view of a part of a strip of spangles after it has been sewed upon the fabric; Fig. 5 is a view similar to that of Fig. 3 but showing the device for simultaneously attaching two strips of spangles; Fig. 6 is a view of Fig. 5 taken from the right; 40 Fig. 7 is a view showing the appearance of the two strips of spangles after they have been attached to the fabric by the device of Figs. 5 and 6; Fig. 8 is a view taken from the underside of Fig. 7; Fig. 9 is a perspective view of the device of my invention as used for attaching a single strip of spangles; Fig. 10 is a similar view of my device when arranged for attaching a pair of strips of spangles; Fig. 11 is a section taken along the 45 line 11—11 of Fig. 10; Fig. 12 is a detail

showing a plan view from below of the block 12.

Referring to the drawings the head, 1, of the machine is provided with the usual holding member, 2, for the needle, which member 60 is adapted to be reciprocated vertically in the usual manner. A member, 3, usually employed in machines of this type to carry a suitable needle guide is also present, but the needle guide is removed and replaced by the 65 device, 4, of my invention, which comprises, in substance, a combined needle guide and a guide for the strip of spangles. This guide 4 comprises structurally a clamping bar 5 having vertically arranged slots, 6 and 7, 70 and a central bearing stud 8. Threaded spindles 9 and 10 attached to the member 3, and provided with clamping screws, cooperate with the two slots, 6, 7, to attach the clamping bar 5, to the head of the machine. 75 By mutual adjustment of the two clamping screws of the two spindles 9 and 10, clamping bar 5 may be rocked upon the stud 8 so as to accurately adjust the needle guide in correspondence with the needle. 80

The lower end of the clamping bar is provided with an inwardly bent extension 11 which carries at its bottom the guides proper previously referred to, namely, the needle guide and the guide for the strip of spangles. 85 These guides comprise substantially a relatively thin flat block 12 held with its plane perpendicular to the bed of the machine and provided with an open longitudinal slot 13 extending from the bottom almost to the top of the block; this slot is slightly deeper on one side than on the other and this maximum depth is substantially equal to the diameter of the spangles. The top of the slot at the side of minimum depth, which is preferably the side away from the member 11, is pierced with a hole 13' into which the needle is introduced and which serves to guide and determine the vertical line in which the needle works. This hole 13' is so located 95 upon the top of the block that it partially overlaps the inner edge of the slot which edge is grooved beneath the hole so as to correspond therewith; the needle reciprocates in this groove and against the inner wall of the slot. The top of the slot 13, on the left of hole 13' is gently curved upwardly and outwardly (as at 13", Figs. 2 and 3) and a wire 14 supported by the block just above this curved portion extends up- 105 110

- wardly and outwardly and terminates in an elongated slot 15 arranged parallel to the slot 13 in a plane, preferably, parallel to the bed plate.
- 5 The strip of spangles shown in the drawings is the usual well known article of commerce in which a series of flat circular spangles, or pairs of spangles, is threaded upon a thread so as to hold the spangles permanently in the same relative position to one another.
- 10 In the operation of my invention the strip of spangles, 16, to be attached to the fabric is wound upon a spool (not shown) suitably held in the usual manner upon the machine.
- 15 The end of the strip is threaded down through the tube 17 in the usual manner, then through the slot 15 and then into and through the slot 13 of the block 12. The
- 20 cord side of the spangles should be facing the groove of the needle guide 13. By reason of the two slots 13 and 15 the strip of spangles is held on edge against the bed plate. The fabric to which the spangles are
- 25 to be attached having been positioned, the machine is operated in the usual manner and the needle 18 as it descends in the needle guide and groove will pass through the system of cords 19 which holds the spangles together and into the fabric. As the operation
- 30 of the machine is continued the strip of spangles is sewed fast to the fabric. By reason of the constant tension on the sewing threads the spangles, as soon as they pass
- 35 out of the slot 13, begin to pass from the vertical position and eventually are drawn flat against the fabric. The stitch which holds the spangles fast upon the fabric is entirely invisible from the upper side of the
- 40 fabric as appears from Fig. 4. The strip of spangles may be placed upon the fabric so as to embody any desired design by rotating the head of the machine by means of the usual crank holder.
- 45 The guide for use in attaching a pair of spangle strips to the fabric is very similar to the one just described for a single strip except that a pair of slots is provided in the
- 50 guide block, one slot for each strip of spangles, while the needle guide is widened (across the length of the strip of spangles) in order that the needle may be oscillated at each alternate stitch so as to alternately stitch through the threads of the two strips.
- 55 More in detail the double guide comprises the block 20, held at the bottom of member 11, as before, and provided with a wide slot 21 and an elongated needle guide, 22, at right angles to the slot. This slot, 21, is in
- 60 reality two slots, there being a thin central partition, 24, in one side of the slot dependent from the roof of the slot 21. At one end of the block 20 is a guide 25 concaved inwardly toward the block and held upwardly and outwardly from the block by an arm 26.

In operation the two strips of spangles are held by suitable spools (not shown) fixed upon the machine and carried down the central tube 17 with their connecting threads adjacent and with the strips flat upon one another. Reaching the guide 25 one strip is carried upon one side of arm 26 and the other on the other side of said arm and then down and around under the end of block 20 and through the slots 21. By reason of the connecting threads being adjacent the spangles themselves will be pushed away from one another and against the outer walls of the slot 21. As the two strips pass the guide 25 they are positioned respectively by the pairs of grooves 25' and 26', the members of each pair being cut respectively in the guide 25 and the block 20. The needle, 18, as it reciprocates vertically, lies at one side of slot 22 so as to pass through the connecting thread of the strip of spangles lying on the corresponding side of slot 21, and then, at the next stitch, lies at the other side of the slot 21, so as to pass through the connecting thread of the second strip of spangles, and so on alternately. Each strip, is therefore, sewed fast to the fabric although the same thread is used to attach both strips. Because the strips lie so close together as they pass through the guide they will, after they are stitched upon the fabric and pass from the guide, incline toward and upon one another so as to produce a unitary strip of spangles of width nearly double that of a single strip; the center line of this double strip will be raised so that the strip will be triangular in cross section. The double strip, like the single strip first referred to, may be stitched to the fabric in any desired ornamental design by rotating the head of the machine in the usual manner by the usual crank holder.

In making the device of my invention I do not need to make it exactly as shown and described so long as the various guiding elements are provided and changes of form may be made within the scope of the following claims.

I claim—

1. In a machine of the type specified, a device whereby a strip of spangles may be stitched to fabric comprising a needle guide and means for guiding the strip of spangles on to the fabric with the length of the strip parallel with and the plane of the strip perpendicular to said fabric and into and at one side of the needle guide so that the needle will pass through the cord holding the spangles together but will clear the spangles.
2. In a machine of the type specified, a device whereby a strip of spangles may be stitched to fabric comprising a block adapted to be attached to the head of the machine and slotted from below to a depth substantially equal to the diameter of the spangles,

means for guiding the strip into said slot, and means for guiding the needle within said slot so as to pass through the cord holding the spangles together but so as to 5 clear the spangles.

3. In a machine of the type specified, a device whereby a strip of spangles may be stitched to fabric comprising a combined needle guide and strip guide adapted to be 10 attached to the head of the machine the strip guide including a slot for holding the strip of spangles on edge against the fabric with the spangles at one side of the needle guide, in combination with means for introducing 15 the strip into said slot.

4. In a machine of the type specified, a device whereby a strip of spangles may be stitched to fabric comprising a block provided with a guide for the needle and a slot 20 opening from below for holding the strip on edge against the fabric the needle guide opening into the top of the slot and away from the side thereof against which lie the spangles proper.

25 5. In a machine of the type specified, a device whereby spangles arranged in strip form may be stitched to fabric, comprising a block having a slot opening from below, means for guiding a pair of strips with 30 their connecting cords adjacent into said slot

and an elongated needle guide transverse to said slot and opening into the top thereof.

6. In a machine of the type specified, a device whereby a strip of spangles may be stitched to fabric comprising a needle guide 35 provided with a slot parallel with and intersecting the path of the needle and means for guiding the strip into said slot, said slot being arranged to maintain the spangles wholly to one side of said needle path so 40 that said needle will pass through the cord holding the spangles together but will clear the spangles.

7. In a machine of the type specified, a device whereby a strip of spangles may be 45 stitched to fabric comprising means for guiding the strip so as to lie on edge with respect to said fabric and means for guiding the needle in a path parallel with the plane of the strip but slightly to one side of 50 the spangles so as to pass through the cord holding the spangles together while clearing the spangles.

In testimony whereof I have hereunto set my hand in the presence of two subscribing 55 witnesses.

JOHN FINK.
